CLAIM

The ornamental design for a hinge for furniture, as shown and described.

DESCRIPTION

FIG. 1 is a perspective view of the top, front and right side of a hinge for furniture showing my (our) new design; FIG. 2 is a perspective view of the top, rear and left side thereof; FIG. 3 is a front view thereof; FIG. 4 is a rear view thereof; FIG. 5 is a left side view thereof; FIG. 6 is a right side view thereof; FIG. 7 is a top plan view thereof; FIG. 8 is a bottom view thereof; FIG. 9 is a cross-sectional view thereof; FIG. 10 is a partially enlarged view thereof, at the call-out box shown in FIG. 6; FIG. 11 is a front view thereof, where an arm portion is rotated; and, FIG. 12 is a perspective view thereof, in a position of use. The broken lines in the drawings illustrate portions of the hinge for furniture which form no part of the claimed design.
